UNITED STATES PATENT OFFICE.

BENJAMIN L. TOQUET, OF WESTPORT, CONNECTICUT.

ELECTRICAL CONNECTOR.

SPECIFICATION forming part of Letters Patent No. 557,037, dated March 24, 1896.

Application filed December 28, 1895. Serial No. 573,635. (No model.)

To all whom it may concern:

Be it known that I, BENJAMIN LOUIS TOQUET, a citizen of the United States of America, and a resident of Westport, Fairfield county, Connecticut, have invented an Improved Electrical Connector, of which the following is a specification.

The object of my invention is to provide for electrical conducting-wires a simple, inexpensive, and easily-applied joint or connector whereby a perfect mechanical and electrical connection can be made.

In the accompanying drawings, Figure 1 is an outside view of one form of my connector as ready for use. Fig. 2 is a longitudinal section of the tube, showing the ends of the metallic conductors which are to be connected in place, but before the joint is made. Fig. 3 is a sectional view of the same after the joint has been made. Fig. 4 is a corresponding outside view of the same. Fig. 5 is a view at right angles to Fig. 4 and showing one half of the tube in section. Figs. 6, 7, and 8 are transverse sectional views at the several points indicated in connection with Fig. 5. Figs. 9 and 10 are views of modified forms of my connector drawn to a smaller scale.

Referring to Figs. 1 and 2, A and A' indicate the bare ends of the copper or other electrical conductors to be connected, while B is the tube or sleeve (preferably of similar metal) by means of which the joint is effected. The internal diameter of the connecting-tube B for a given gage of wire is of a size to just allow of the convenient insertion of the ends of the wires A and A' of that gage, as indicated in Fig. 2, the fit being a close one.

When the ends of the wires have been inserted in the tubes until they nearly meet about the center, I indent both the tube and the contained wires by a suitable tool, such as a pair of pliers, which will crush each wire end at one or more points within the tube to a greater width than the normal internal diameter of the tube or sleeve.

In Figs. 3 to 5 I have shown the tube and contained wire ends as crushed in together at four points, two for each wire end. The action is such as to not only crush and flatten out the tube or sleeve B in forming the opposite indentations b, as shown in Fig. 4, but also the parts of the wire ends between these op-

posite indentations are indented and crushed and flattened out at the same time, producing shoulders or enlargements x and y in the wire ends and tubes, as indicated clearly in Figs. 3, 5, 7, and 8. By these means I not only secure a good mechanical joint, which, owing to the retaining shoulders or enlargements x and y, will stand any tensile strain which the conductor itself will sustain, but I also get a good electrical joint, because of the metallic union brought about by the crushing together and flattening jointly of the wires and tube. These connectors can be made either straight, as shown in Fig. 1, or in any other suitable form, such as the T form for jointing three wires, as illustrated in Fig. 9, or the cross form illustrated in Fig. 10. The connection may be used in terminals and branches, as well as connecting two wire ends, as will be readily understood. When straight connectors are used, such as illustrated in Figs. 1 to 5, I prefer to provide each tube with a central internal stop or stops z, which may be most conveniently formed by slightly indenting the tube, as shown in Figs. 1, 2, 4, 5, and 7. The purpose of these stops is to locate the ends of the wires at desired points within the tubes without having to measure them, and thus time will be saved in making connections.

I am aware that tubes or sleeves have been used for electrical wire-connectors, but in all such cases, so far as I am aware, it has been sought to secure the necessary electrical and mechanical connection by twisting or bending the tubes. Either of these operations involves no little labor and time and the use of powerful instruments, and the joint when finished does not offer a perfect safeguard against pulling apart and does not insure a perfect electrical connection. In my joint, however, since the wire ends are flattened within the tube until at points their width exceeds the normal inside diameter of the tube, it is practically impossible to pull the joint apart without either breaking the wire or the tube, and, as I have already explained, this same crushing and flattening of the tube and contained wires insures a good electrical joint. The joint can be applied very quickly and with small labor, a pair of nippers only being required. It can be used in places where there would not be room to either twist

or bend such connection, as it is only necessary, with my joint, to reach it with the end of the tool. The joint can be easily tapped and is not cumbersome. It can be used to 5 splice a broken wire, as the wires do not overlap each other.

I claim as my invention—

1. A joint for electrical conductors consisting of a tube fitting over adjoining ends of the 10 conductors, both tube and conductor ends being indented, widened and crushed together at points, substantially as described.

2. A tube for a joint for electrical conductors indented to form an internal central stop or stops, substantially as and for the purpose 15 described.

In testimony whereof I have signed my name to this specification in the presence of two subscribing witnesses.

BENJAMIN L. TOQUET.
